GOLF MACHINE

Glenn L. Thompson, Chicago, Ill., assignor of forty-nine one-hundredths to Michael G. Lisak, Chicago, Ill.

Application February 3, 1934, Serial No. 709,550

11 Claims. (Cl. 273—35)

This invention relates to a golf machine, and particularly to a mechanism to enable persons interested in improving their game to practice driving, and to become proficient therein. In this connection, the player must usually drive the ball true and straight toward its objective. It is desirable, therefore, in practicing the drive stroke that the machine indicate departures from a good drive, such as a hook, or a slice, so as to enable the player to determine what is wrong in his technique, or style of play and consequently take appropriate measures to correct his play.

Accordingly, the objects of the invention are to provide an improved golf practice machine; to provide a machine embodying mechanism that will accurately register a hook or a slice; to provide a machine that will indicate yardage or theoretical distance of the ball driven; and lastly, but of the greatest importance, to provide an ingenious means for mounting the ball member that is to be struck by the driving golf club. Other objects will, of course, become obvious to those skilled in this art, as the disclosure is more fully made.

Briefly, these desirable objects may be achieved in providing a base carrying a lever to which is connected, in a novel manner, a golf ball or appropriate ball member carried in a position approximating the usual height from which a golf ball is driven in the actual game of golf. This lever not only swings pivotally when the ball is struck, but also can turn left or right about its lengthwise axis. The lever includes a member utilizing such turning movement to actuate mechanism and an indicator to show a hook or a slice. Further, the lever is connected with mechanism to register yardage in accordance with the force of impact of a club on the ball. Of course, other features of construction are involved, but for the present, so much will suffice to give a general understanding of the invention.

In the accompanying sheets of drawings illustrating a practicable form of the invention:

Figure 1 is a general plan view of the improved golf machine;

Figure 2 is a longitudinal and substantially central, sectional view through the machine;

Figure 3 is a cross sectional view through the machine as seen along the section line 3—3 appearing in Figure 1, looking in the direction of the arrows;

Figure 4 is a cross sectional view through the machine as seen along the section line 4—4 appearing in Figure 2 looking in the direction of the arrows;

Figure 5 is a cross sectional view through the machine as seen along the section line 5—5 appearing in Figure 1, looking in the direction of the arrows; and,

Figure 6 is a cross sectional view through the machine as seen along the section line 6—6 appearing in Figure 1, looking in the direction of the arrows.

As shown in the drawings, the body of the machine comprises a shallow box 10 of appropriate shape so that it will rest stably on a floor or other level surface, where the machine is to be used. The box 10 has a flat horizontal top 11 which at its front end, or to the left as viewed in Figures 1 and 2, is slotted along the longitudinal median line as at 12 to provide a space for fore and aft swinging movement of a sleeve 13 whose lower end is securely anchored in a cylindrical member 14 rockable about a transverse axis. This cylindrical member is formed with a row of gear teeth 15, said gear teeth resting on and meshing with a pair of spaced gear rack bars 16 lying slidably on the floor of the box.

Carried for turning movement about its lengthwise axis in the sleeve 13 is a cylindrical rod-like member 17 having its lower end 18 reduced to form a shoulder seated on a coil spring 19 encircling the reduced portion 18 as shown. The spring 19 is held in the lower end of the sleeve 13 in any appropriate manner. The upper end of the member 17 is also reduced and threaded as at 20 so that a ball element 21 having a substantially spherical metal core 22 may be securely but detachably attached to the upper end of the shank 20 as appears best in Figure 2. A rubber plate or mat 23 overlies the top 11 and has a recess 24 in its front edge to provide a space for movement of the parts 13 and 17 which together constitute the ball carrying lever, or support.

The part 17 has secured to it a forwardly extending trip 25 which moves with the part 17 and extends ahead through an appropriate slot 26 formed in the sleeve part 13. This trip is formed with a notch 27 for a purpose later to appear. Mounted in the forward portion of the box and on each side of the passageway 12, and in alignment transversely, is a pair of rock shafts 28 (see Figures 2 and 3) having their adjacent inner ends bent to form cranks 29, while connected to the outer end of each shaft is a pad lever 30 made fast to the respective shafts 28. Each shaft 28 adjacent the crank 29 thereon carries fast thereon an indicator or target member 31 which op-

erates under openings 32 respectively formed in the top 11 of the box on each side thereof.

The cylindrical member 14 has trunnions 14a at each end thereof which are journaled in brackets 33, as shown best in Figure 4, said brackets 33 being cushioned by being mounted on rubber blocks 34. Rearwardly of the cylinder 14 the racks 16 merge into a solid slide member having an upturned rear end 35 as shown in Figures 1 and 2, said slide member operating under a hold down plate 36 having a rubber facing 37 on its back side for cooperation with the front edge of the upturned portion 35. The rear face of the portion 35 is formed with a rearwardly extending cylindrical shank 38 carrying a cushion spring 39 whose other end is mounted on an alined shaft 40 slidably mounted in a bracket 41 suitably secured to the floor of the box 10.

On the rear side of the bracket 41 the slide shaft 40 has secured thereto a block 42 which in turn has secured to it a ratchet bar 43 that can slide through a passageway formed in the bracket 41 as shown in Figure 5. Toward its rear end the bar 43 is formed with gear teeth 44 in mesh with a small gear 45 formed on a vertical shaft 46 journaled in the box 10. Above the gear 45 the top 11 of the box 10 is recessed as shown in Figure 6, said shaft 46 projecting upwardly thereinto to carry an indicator needle 47 operating over a dial plate 48 marked off to show yards of drive.

The rear end of the slide shaft 40 is carried in a bracket 49 and made fast to the rear end of the shaft 40 in back of the block 49 is a block 50 connected securely to the rear end of the rack bar 43. A cushion spring 51 may be located between the rear end of this structure and the rear wall of the box as shown in Figure 1.

The front bracket 41 carries a spring pressed dog 52 to engage in the ratchet teeth on the bar 43. A lever 53 is provided to be operated from the top of the box 10 to release the spring pressed dog 52 from the ratchet teeth on the bar 43. A spring 54 encircles the rear end of the shaft 40 between the bracket 49 and a nut 55 is threadedly mounted on the shaft to enable the compression of the spring 54 to be adjustably set. The use and operation of the machine will now be described.

The player who is to use the machine stands in the proper position to strike the ball 21 which is shown in Figures 1 and 2 in the normal or starting position. If the ball is properly struck for a straight and true drive without any hook or slice, then the lever 17, 13 will pivot forwardly, causing the gear structure 15 to drive the rack structure 16 toward the rear. Thus the part 35 pushes against the cushion spring 39 which is relatively light, until the lost motion space between the shank 38 and the front end of the shaft 40 is taken up. Thus the shank 38 abuts the shaft 40 and drives it back and as a result the blocks 42 and 50 which are secured to the shaft 40 are caused to carry the bar 43 back. Thus the gear rack 44 drives the gear 45 and shaft 46 to move the indicator needle 47. When the bar 43 has moved rearwardly its maximum distance, the spring pressed pawl 52 locks in the ratchet teeth on the bar 43 to hold all the parts mentioned locked. The player then notes the indicator 47 to get the yardage of his drive. To reset the machine he steps on the release lever 53 thereby releasing the pawl 52 which causes the cushion spring 51 to reset all parts for another drive at the ball 21.

If the ball 21 is not squarely hit and a spin is imparted thereto by the driving golf club, then the lever 17, 13 pivots forwardly as before, but in addition the portion 17 of the lever is caused to turn one way or the other about its lengthwise axis in the sleeve 13, causing the trip 25 to turn likewise and engage one or the other of the two cranks 29 depending upon the direction of twist imparted when the ball was struck. It is this twist in striking the ball that determines a hook 10 or a slice. Thus, the trip 25 strikes a crank 29 to rock the connected shaft 28 which brings a target 31 into display position under the opening 32 adjacent which is a marking to indicate hook or slice. The notch 27 in the trip 25 engages under 15 the sleeve 13 to lock under pressure from the spring 19 so that the trip is held in position to engage a crank 29. Thus the target 31 will be locked in display position and held thereby a spring 29a until the player releases the same by operating 20 the appropriate lever 30. The indicator 47 is, of course, also operated in the way previously described to show yardage in accordance with the force of impact on the ball 21.

The rubber blocks 37 prevent excessive jar or 25 pounding when the parts are restored to playing position under the force of the spring 54. The lost motion or take up space between the shank 38 and shaft 40 is important as it cushions the contact of the club with the ball and permits the 30 player to carry or follow through in his swing with the assurance that the club will not be broken no matter how hard he strikes the ball.

The mounting of the ball 21 on the lever structure is of the utmost importance to the proper 35 working of the machine. The ball, due to its special hard core 22, is securely held on the lever part 17. Further, the lever part 17 turns freely in the sleeve part 13 to enable registering a twist causing slice or hook in the drive. In the event 40 the ball is topped, the downward force imparted to the ball mounting is absorbed by the spring 19 and the rubber blocks 34 in an obvious manner, to prevent any possible damage to the ball mounting under such a condition. Because of the 45 threaded connection 20 a badly cut or chipped ball can quickly be removed and replaced.

From this disclosure it will now be seen that an improved golf machine has been provided which achieves all of the desirable objects here- 50 tofore recited.

It is the intention to cover herein all such changes and modifications of the example herein chosen for purposes of illustration as do not depart from the spirit and scope of the invention 55 as hereinafter claimed.

What is claimed is:

1. In a golf machine, a body, a lever swingably carried by the body, and support means included in the lever to carry a ball, said support means 60 being mounted for turning movement about its lengthwise axis with the ball independently of the lever.
2. In a golf machine, a body, a sleeve pivotally mounted in the body, a ball supporting member movable with the sleeve and independently turnable therein, and a ball on said supporting member.
3. In a golf machine, a pivotally mounted normally upright elongated sleeve, a ball support 70 rockably mounted in the sleeve and movable therewith when it pivots, and cushion means to enable the sleeve and support to have relative up and down movement.
4. In a golf machine, a pivotally mounted ball 75

support, said support also being turnable about its axis, a hook and slice indicating mechanism, and a trip on the support, said trip operating said indicating mechanism.

5 5. In a golf machine, a movably mounted ball support, hook and slice indicating means, means comprising a trip on the support to operate the indicating means directly from the support, means associated with the trip to lock the indicating means in indicating position, and means to release the lock means.

10 6. A golf machine comprising a body, an elongated ball support associated with the body for turning movement axially of its lengthwise axis, 15 rockable hook and slice indicators adjacent the support and carried by the body, and means directly engageable between the indicators and support to set the indicators in indicating position when the support turns.

20 7. A golf machine comprising a body, an elongated ball support associated with the body for turning movement axially of its lengthwise axis, a trip movable with the support, and rockable hook and slice indicators including cranks adjacent the support and carried by the body, said trip being directly engageable with the cranks to set the indicators in indicating position when the support turns.

25 8. In a golf machine, a horizontal body, an elongated normally substantially upright ball support associated with the body, and means

whereby said support may have pivotal movement, turning movement about its lengthwise axis, and bodily up and down axial movement.

9. In a golf machine, a horizontal body, an elongated normally substantially upright ball support pivotally connected adjacent its lower end to the body, and means whereby in addition to pivoting, the support may rock about its lengthwise axis and move bodily up and down.

10. In a golf machine, a movably mounted 10 substantially upright elongated ball support, hook and slice indicating register elements associated with the machine for movement from non-regis- 15 tering to registering positions, said ball support having rocking movement about its lengthwise 15 axis and including a member movable therewith to move one or the other of the register elements into registering position.

11. In a golf machine, a horizontal body, an elongated substantially upright ball support as- 20 sociated with the body for pivotal swinging move- 25 ment, rockable movement about its lengthwise axis and bodily translational movement about its lengthwise axis, means to cushion the bodily movement thereof, yardage indicating mech- 25 aism, reciprocatory means to operate said indicating mechanism, said last means being operated by the pivotal swinging movement of the support.

GLENN L. THOMPSON. 30
